UNITED STATES PATENT OFFICE.

FRANK L. MOORE, OF CHICAGO HEIGHTS, ILLINOIS, ASSIGNOR TO EMILY E. SMITH, OF SAME PLACE.

MACHINE FOR FORMING WHEEL-HUBS FROM TUBULAR BLANKS.

SPECIFICATION forming part of Letters Patent No. 638,183, dated November 28, 1899.

Application filed January 9, 1899. Renewed November 6, 1899. Serial No. 736,062. (No model.)

To all whom it may concern:

Be it known that I, FRANK L. MOORE, a citizen of the United States, residing at Chicago Heights, in the county of Cook and State of Illinois, have invented a new and useful Improvement in Machines for Use in Forming Wheel-Hubs from Tubular Blanks, of which the following is a specification.

My invention relates particularly to an improvement in machines for use in the first step of the process of forming wheel-hubs from tubular blanks.

The manner of forming a wheel-hub from a tubular blank, it may be stated, is first to operate upon the blank with a machine capable of rolling or bulging the metal out to form two annular enlargements, ridges, or corrugations at the required distance apart to form the spoke-attachment flanges, and, after said ridges have been formed, to operate further upon the blank with suitable dies to compress said ridges in the direction of the length of the blank, and thereby to flatten them into a plane perpendicular to the axis of the blank, when they can be perforated by means of a punch or multiple drill for reception of the spokes.

My object is to provide a machine of simple construction capable of rapidly performing the first operation mentioned and overcoming many of the objections present in the operation of machines commonly used for this purpose—such, for instance, as an objectionable deforming of the blank by buckling or twisting.

I accomplish my purpose by providing mechanism of such construction that the blank is clamped between the relatively movable sections of a rotatable die provided with interior annual grooves and is operated upon from the interior preferably by a roller-equipped shaft movable parallel to its axis to cause said rollers to press or bulge the metal outward into the annular grooves of the closing die.

In the accompanying drawings, Figure 1 is a view in side elevation of my improved machine, the driving-pulley on one shaft and a link connecting the other two shafts being removed and the shafts shown in section; Fig. 2, a vertical section taken as indicated

at line 2 of Fig. 4, the gears being shown in elevation; Fig. 3, a transverse vertical section taken on line 3 of Fig. 2; Fig. 4, a longitudinal horizontal section on line 4 of Fig. 1; Fig. 5, a longitudinal section of the tubular blank from which the wheel-hub is formed, and Fig. 6 a similar section of the blank after it has been operated upon by my improved machine.

The machine comprises, preferably, a horizontally-disposed frame A, secured to a suitable bed or base-block B by bolts *t*; a separable two-part die C, supported within a rotating member, preferably a gear D, said gear being provided with hub extensions D', journaled in two-part bearings A', forming part of the fixed frame A; a gear E, fixed by a key *s* to a drive-shaft F, upon an enlargement F' thereof, said shaft being journaled in a two-part bearing E' and equipped with a driving-pulley F², and a roller-equipped two-part shaft G G' within the die C and supported by arms or links H H', non-rotatably carried by a shaft H², itself non-rotatably supported in a slide H³, longitudinally movable on a guide A², forming a part of the frame A and connected with an adjusting-screw H⁴, equipped with a hand-wheel H⁵ and rotatable, but immovable longitudinally, within a standard H⁶, secured to an end of the frame A.

The die C, comprising two parts C' and C², is conveniently made in box form to slip into a central perforation or die-chamber *r*, of rectangular cross-section, in the gear D, where it is held against longitudinal movement by a pin or key *r'*, Figs. 2 and 4, extending through the gear and engaging a transverse groove on the lower surface of the box-like die. The part C' of the die bears against the adjacent vertical wall of the die-chamber, while the part C² is movable parallel to the axis of the gear D to permit the separation of the two die-sections for insertion of a hub-blank. Two short arms or lugs *p p'*, pivotally secured by pins *p²* to the gear D and provided with cam-surfaces *p³*, eccentric to the pins *p²*, serve to force the die-section C² close to its companion member to clamp the hub-blank between said die members.

The section G of the two-part shaft within

the die C comprises a portion n , fixed to the arm H, into the inner end of which screws a portion n' , provided at one end with a socket and toward the other end with a reduced portion n^2 , upon which is journaled a roller n^3 . The reduced portion n^2 is of smaller diameter than the adjacent portion of the part n , so that the roller is confined against longitudinal movement on the shaft in either direction.

10 The section G' of said shaft comprises a part m , fixed to the arm H', and a portion m' , screwing into the inner end of the part m and provided with reduced portions m^2 and m^3 , the former of which is equipped with a roller m^4 15 and the latter of which fits into the socketed end of the adjacent shaft-section when the parts are together, as illustrated.

The die C is provided with inner circumferential grooves or channels l , with which 20 the rollers mentioned register and into which the bulging metal of the blank is received as the shaft G G' is moved parallel to itself by the hand-wheel H⁵ while the gear D and the die within it are being rotated.

25 The arm H' is readily movable on the shaft H², to which it is secured by a winged set-screw k , said shaft being allowed to project a sufficient distance beyond the arm to permit sufficient latitude of movement for the 30 inner end of the shaft-section G' to clear the end of the die C in order that the arm H' may be swung about the shaft H² and the way left clear for the removal or insertion of a blank. A feather j on the shaft H² and fitting with- 35 in grooves on the interior surfaces of the shaft-receiving perforations of the parts H³ and H' serves to prevent rotation of the parts with relation to each other. A set-screw j serves to hold the shaft H² against longitudinal 40 movement.

Adjustment set-screws h on the portions A' of the fixed frame serve to limit the movement of the slide H³ toward the left, marking the location of the shaft G G' concentrically 45 with the die, and adjustable set-screws g on the slide serve to limit the movement of the slide toward the right, being in such position as to strike against the standard H⁶ at the instant when the metal in contact with the 50 rollers has been forced into close contact with the grooves l .

The operation is as follows: While the shaft G G' is in a position concentric with the die C, the arm H' is loosened on the shaft H² by 55 unscrewing the set-screw k and is then moved outward to permit the shaft-section G' to be swung away from the die. The pivoted lugs or clamping members $p p'$ are then swung outward to permit the die-section C² to be separated from its companion member to allow a hub-blank I to be introduced or removed, as the case may be. When the blank is properly located within the die, the pivoted lugs are forced inward and by their cam or eccentric 60 action force the die-section C² toward the section C'. The shaft-section G' is then returned to and secured in its proper position,

after which the rotating parts are set in motion, the gear D serving to rotate the die C. The screw H⁴ is then turned to the right 70 and through the medium of the slide H³, shaft H², and arms H H' the shaft G G' is moved out of center to cause the rollers $n^3 m^4$ to engage the interior of the rotating tubular blank. Pressure sufficient to produce the annular 75 ridges d on the exterior surface of the blank (shown in Fig. 6) is readily applied at the wheel H⁵, and the blank is taken from the machine in perfect order for the next operation. 80

Changes in details of construction within the spirit of my invention may be made. Hence I wish to be understood as intending no limitation by the particular and minute description given above. For instance, an obvious 85 change in the construction would be to permit the shaft G G' to rotate with the rollers thereon, the latter being firmly fixed thereto, though disadvantages would follow such a change. In the appended claims I desire to 90 be understood as intending by the use of the term "roller-equipped shaft" to include a shaft whereupon the rollers or their equivalent are firmly fixed.

While the machine is intended principally 95 for use in the formation of wheel-hubs, the invention is not limited to this particular purpose.

What I claim as new, and desire to secure by Letters Patent, is— 100

1. The combination of a frame, a rotatable gear journaled in the frame provided with a die-chamber, means for imparting motion to the gear, a die comprising a plurality of longitudinally-separable parts carried by the gear, means for fixing the die parts in their closed position, a slide connected with the frame, a roller-equipped shaft extending through said die and supported at both ends from said slide, and means for moving said slide to produce eccentricity in a required degree between shaft and die, substantially as and for the purpose set forth. 105

2. The combination of a frame, a rotating member journaled therein, a die carried by 115 and rotating with said member and provided with inner circumferential grooves, a separable two-part roller-equipped shaft extending into said die the shaft parts being sustained from supports at opposite ends of said die, and means for supporting said shaft and producing eccentricity between shaft and die, substantially as and for the purpose set forth. 120

3. The combination of a frame, a rotating member journaled therein, a die carried by 125 and rotating with said member and provided with inner circumferential grooves, a shaft extending through said die provided with loosely-journaled rollers registering with said grooves, and means for supporting said shaft 130 and producing eccentricity between shaft and die, substantially as and for the purpose set forth.

4. The combination of a frame, a die-bear-

ing gear journaled therein, a drive-gear connected with said first-named gear, a die provided with inner circumferential grooves, a slide connected with the frame, a separable 5 two-part shaft extending into said die provided with longitudinally-confined loosely-journaled rollers, said shaft being supported from said slide, and means for moving the slide to produce eccentricity in a required degree between shaft and die, substantially as and for the purpose set forth.

5. The combination of a frame, a die-bearing gear journaled therein, a drive-gear connected with said first-named gear, a die provided with inner circumferential grooves, a slide connected with the frame, a shaft fixed to said slide, a two-part shaft extending through said die, an arm fixedly secured to the slide-supported shaft and to one part of 15 the two-part shaft, an arm slidably and non-rotatably connected with said slide-supported shaft at its opposite end and supporting the second half of the two-part shaft, rollers journaled on the two-part shaft, and means for 20 moving the slide longitudinally of the machine-frame to move the shafts parallel to themselves, substantially as and for the purpose set forth.

6. The combination of a frame A, journaled

gears E and D, two-part die C provided with 30 inner circumferential grooves, means for fixing the die parts in their closed position, roller-equipped shaft G G' extending through said die, slide H³, shaft H², arm H connecting the shaft ends at one side of the machine, 35 arm H' slidably and non-rotatably joined to shaft H² and bearing part G' of shaft G G', and screw mechanism connecting frame and slide for producing eccentricity of shaft G G' with relation to die C, substantially as and 40 for the purpose set forth.

7. The combination of a frame, a die comprising a plurality of longitudinally-separable parts provided with inner circumferential grooves, means for fixing the die parts in 45 their closed position, means for supporting and rotating the die, a roller-equipped shaft extending through the die and projecting beyond the ends thereof, and means connected with the two ends of the shaft and movably 50 connected with the frame for supporting the shaft and producing eccentricity with relation to the die, substantially as and for the purpose set forth.

FRANK L. MOORE.
